UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

INSULATOR.

1,236,188.

Specification of Letters Patent. Patented Aug. 7, 1917.

Application filed December 21, 1912. Serial No. 737,988.

To all whom it may concern:
Be it known that I, EDWIN N. LIGHTFOOT, a citizen of the United States, residing at New York, in the county of New York and State of New York, have invented new and useful Improvements in Insulators, of which the following is a full, clear, concise, and exact description, reference being had to the accompanying drawing, forming a part of this specification.

This invention relates to an improved insulator.

More particularly the invention relates to an insulator which, among other uses, may be employed as an insulating bushing, an insulator and terminal for an electric circuit or as an insulator and support for live conductors.

An object of the invention is to provide an insulator which may be completely assembled during manufacture, thereby facilitating the mounting of the device for use.

Another object is to provide an insulator which may be readily and easily mounted upon its support.

Another object is to provide an insulator especially adapted for use where high temperatures are encountered.

Another object of the invention is to provide an insulator which is waterproof.

Another object of the invention is to provide an insulator accomplishing the objects above enumerated, which may be economically manufactured.

Several embodiments of the invention are illustrated in the accompanying drawings, in which:

Figure 1 is a section of one form of the device adapted for use as an insulating bushing.

Fig. 2 is a front elevation of the bushing illustrated in Fig. 1.

Figs. 3 to 12 illustrate modifications.

Figs. 1 and 2 illustrate the insulator in its use as an insulating bushing. The insulator comprises a washer 1 of insulating material, preferably mica, although fiber or other material may be used, a thimble 2, preferably of metal, having an annular recess 3 within which the outer edge of the insulating washer is clamped, as at 4 and 5, and an eyelet 6, preferably of metal, embracing and clamping the inner edge of the washer as at 7 and 8. The thimble 2 is

preferably provided with a sleeve 9 which may be inserted through the supporting wall or member 10 and formed outwardly as at 11 to secure the insulator firmly in place. Suitable protecting washers 12 and 13 may be employed if desired.

Figs. 3 and 4 illustrate the insulator adapted for use as a terminal. The eyelet 6 may be extended at one end and bent inwardly as at 14, the sides being mashed together as at 15 and provided with a terminal screw 16. A perforation 17 formed in the bent-in portion 14 permits a conductor to be led through from the inside and attached to the binding screw 16 thereby providing for easy access to the terminal. This feature is especially useful in structures such as electric heaters where the insulator is in the wall of an inclosing box and it is desired to inclose the conductor and still have the terminal readily accessible.

Fig. 5 illustrates a water-proof insulator and terminal in which all openings through the structure are eliminated. In place of the eyelet 6 the inner edge of the insulating washer is clamped between an enlargement 18 and a washer 19 held in place by a nut 20 on the conducting stud or bolt 21 which closely fits the central opening in the washer. Nuts 22 are provided for holding the conductor ends. This form of terminal provides a water-proof structure and also provides for increased capacity.

Fig. 6 illustrates a terminal having a greater capacity than that illustrated in Fig. 3 since in this form the entire central opening of the eyelet is available for carrying conductors. In this form an additional number is used to support the connector terminals. For this purpose the right angled terminal 23 is clamped in place against the insulating washer by the eyelet 6 and is provided with a terminal screw 16. Nuts 24 may be provided for holding conductor ends to the terminal.

Figs. 7 and 8 illustrate a modification in which separate terminals are provided for the external conductors and the conductors which pass through the eyelet from within. In this form a U-shaped member 26 is clamped in place by the eyelet 6 and is provided with a terminal screw 16 on each branch. Either the external supply conductors or the conductors passing through

the eyelet may be disconnected from the terminal without disturbing the connection of the other conductors.

Figs. 9 to 12 illustrate forms of the insulator adapted to support conductors such, for example, as the live parts used in heaters of the radiant type.

Figs. 9 and 10 illustrate a support which is similar in construction to the terminal illustrated in Fig. 3 except, of course, that the opening 17 is dispensed with. The bare conductor, as 27, may be supported by looping over the terminal screw as illustrated in Fig. 9.

Fig. 11 illustrates a further modification in which the portion 15 is bent back to form a supporting hook 28 which may be employed to support a loop of the conductor 27.

Fig. 12 illustrates an additional modification in which the inner or eyelet member 6 is used as the support while the thimble 2 is provided with a flanged sleeve 29 adapted to support a loop of the conductor 27. A supporting stud 30 is passed through the eyelet and headed as at 32 to hold the insulator in place.

The various modifications shown and described are merely for the purposes of illustration as many other modifications may be employed which will fall within the scope of the invention as defined in the claims. Other insulating materials may be used than those mentioned and other means for holding the parts together may be employed.

In any of the forms illustrated the means for attaching the insulator to its support may be arranged in connection with the eyelet member instead of in connection with the thimble.

What I claim as new and desire to secure by Letters Patent of the United States is:

1. An insulator and terminal comprising an insulating washer, a member clamping one edge thereof, a metallic eyelet clamping the other edge thereof, the walls of said eyelet being extended beyond said washer, said extended portion having its walls pressed together and being provided with means for connecting an electric conductor thereto.

2. An insulator and terminal comprising a perforated washer of insulating material, a metallic member clamping the outer edge thereof, and an eyelet clamping the inner edge of said washer, said eyelet having an extension for supporting a binding post and said member being adapted to support the insulator independently of the eyelet.

3. An electric insulator and terminal comprising a perforated disk of insulating material, a metallic member surrounding and embracing the outer edge of the disk, a metallic member embracing the inner edge of the disk at the perforation, one of said members being adapted to support the in-

sulator independently of the other member, and said other member being adapted to form an electrical terminal.

4. An electric insulator comprising a perforated disk of insulating material, a metallic member surrounding and embracing the outer edge of the disk, a metallic member embracing the inner edge of the disk at the perforation, the outer member being adapted to support the insulator independently of the inner member and the inner member forming an electrical terminal. 70 75

5. An electric insulator comprising a perforated disk of insulating material, a metallic member embracing the outer edge of the disk, a metallic member embracing the inner edge of the disk at the perforation, the outer member being adapted to support the insulator and the inner member having a passage therethrough for a conductor and supporting 80 85 a terminal for said conductor.

6. An insulator and terminal comprising a metallic member having an annular enlarged portion flanged over an insulating washer, an eyelet extending through the washer and flanged over the same, said eyelet having an extension supporting a binding post. 90

7. An insulator and terminal comprising a metallic sleeve adapted to extend through 95 an opening in a support and having an enlarged annular portion adapted to engage one side of said support whereby the sleeve may be attached to said support by flanging the end of the sleeve opposite the enlarged portion over the support, an insulating washer in the enlarged portion of said sleeve and an eyelet extending through said washer adapted to support a binding screw. 100

8. A device of the character described comprising a plurality of sheets of thin insulating material having an opening therethrough, a thimble embracing the outer edges of said sheets and compressing them, and an eyelet formed over the inner edges of said opening to further compress said sheets, said eyelet comprising part of a tube, the rest of which is flattened and carries a conductor terminal. 110

9. An insulator and terminal comprising a washer of insulating material, a metallic member clamping the outer edge thereof, and a one-piece eyelet clamping the inner edge of said washer, said eyelet having an extension to which an electric conductor may be connected and said member being adapted to support the insulator independently of the eyelet. 115 120

10. An insulator and terminal comprising a washer of insulating material, a metallic member clamping the outer edge thereof, and a one-piece eyelet clamping the inner edge of said washer, said eyelet having an integral extension to which an electric conductor may be connected and said member 125 130

being adapted to support the insulator independently of the eyelet.

11. An insulator and terminal comprising a washer of insulating material, a one-piece 5 metallic member clamping the outer edge thereof, and a one-piece eyelet clamping the inner edge of said washer, said eyelet having an extension to which an electric conductor may be connected and said member 10 being adapted to support the insulator independently of the eyelet.

12. An insulator and terminal comprising a washer of insulating material, a one-piece metallic member clamping the outer edge 15 thereof, and a one-piece eyelet clamping the inner edge of said washer, said eyelet having an integral extension to which an electric conductor may be connected and said member 20 being adapted to support the insulator independently of the eyelet.

13. An insulator comprising a metallic sleeve adapted to extend through an opening in a support and having an enlarged annular portion adapted to engage one side

of said support whereby the sleeve may be 25 attached to said support by flanging the end of the sleeve opposite the enlarged portion over the support, a perforated insulating washer in the enlarged portion of said sleeve, and an eyelet extending through the 30 perforation of said washer and clamping the inner edge of the washer.

14. An insulator comprising a perforated disk of insulating material, a metallic member 35 clamping the outer edge of said disk and an eyelet extending through the perforation of the disk and clamping the inner edge thereof, said outer member having a portion adapted to be flanged to attach the same to a support. 40

In witness whereof, I have hereunto subscribed my name in the presence of two witnesses.

EDWIN N. LIGHTFOOT.
